UNITED STATES PATENT OFFICE.

GEORGE HENRY NELSON, OF BELVIDERE, KANSAS.

ADJUSTABLE WRENCH.

Application filed September 21, 1923. Serial No. 664,078.

To all whom it may concern:

Be it known that I, GEORGE HENRY NELSON, a citizen of the United States, residing at Belvidere, in the county of Kiowa and State of Kansas, have invented a new and useful Adjustable Wrench, of which the following is a specification.

This invention relates to tools, and more particularly to a novel form of wrench, the primary object of the invention being to provide a wrench which may be readily and easily positioned on a nut, and one wherein all possibilities of the wrench moving with respect to its work are eliminated.

Another object of the invention is to provide means for accurately adjusting the jaws of the wrench with respect to each other, there being provided locking means associated with the adjusting means for holding the adjusting means against movement after an adjustment has been made.

Another important object of the invention is to provide pivoted handle sections which may be readily and easily moved to their active positions.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view of a wrench constructed in accordance with the invention.

Figure 2 is a longitudinal sectional view through the jaws of the wrench disclosing the operating handles in their operating position.

Figure 3 is a sectional view taken on line 3—3 of Figure 2.

Figure 4 is a sectional view taken on line 4—4 of Figure 2.

Referring to the drawing in detail, the device embodies movable jaws 5 and 6, which jaws are formed with cut out portions 7 at their ends and extending transversely thereof to provide article gripping surfaces.

At one end of each movable jaw is a cut out portion extending longitudinally thereof, which cut out portions are designed to provide an end wrench, should it be desired to use the tool as such.

Formed on the rear wall of each jaw are spaced flanges 8 between which the operating handles 9 are pivotally mounted, shafts 10 being provided for supporting the handles 9. As shown the handles 9 are formed with a curved end wall 11 and a relatively straight end wall 12, the curved walls allowing the handles to be moved to their inactive positions, or to positions as shown in dotted lines in Figure 2, when the wrench is used in the usual manner. In order that the handles 9 may be held in their active positions, pins 13 are provided, which pins connect the flanges 8 and restrict movement of the handles.

The jaws 5 and 6 are provided with threaded openings to receive the adjusting screws 13' which may be operated to move the jaws 5 and 6 away from each other, to position them on a nut or bolt to be secured. Carried by one of the jaws is a guide pin 14 that extends through an opening in the opposed jaw to relieve the threads of the adjusting screw of lateral strain and at the same time hold the jaws in direct alignment at all times.

As shown, these adjusting screws are formed with grooves 14', which grooves accommodate the inner ends of the lock screws 15, whereby movement of the adjusting screws will be prevented, after an adjustment has been made.

From the foregoing it will be obvious that by operating the adjusting screws 13', the jaws 5 and 6 may be moved with respect to each other to securely grip a nut or bolt to be positioned. After the adjustment has been made, the locking screws 15 may be properly positioned to lock the jaws against movement, thereby insuring against the wrench slipping from its work while in use.

I claim:

In a wrench, a pair of movable jaws, adjusting screws carried by the jaws for moving the jaws with respect to each other, flanges spaced apart and formed integral with each jaw, operating handles pivotally supported between the flanges and adapted

to swing to positions in parallel relation with the jaws, said flanges having openings, pins adapted to extend through the openings and adapted to engage the operating handles to restrict movement of the operating handles, and a guide pin for holding the jaws in alignment with each other.

In testimony that I claim the foregoing as my own, I have hereto affixed my signature in the presence of two witnesses.

GEORGE HENRY NELSON.

Witnesses:

A. S. LEONHARDT,
H. H. KEITHLEY.
